CONTAINER

Henry M. Dillhoefer, Cleveland Heights, Ohio

Application November 12, 1930, Serial No. 495,109

5 Claims. (Cl. 285—49)

This invention relates to a container, more particularly to a bung ring and its mounting in one wall of a container.

One object of the invention is to provide a container having in one of its walls an improved bung ring and a mounting therefor, these parts having interlocking elements adapted to fixedly connect the bung ring in the container wall.

Another object of the invention is to provide a container having in one of its walls an improved bung ring and mounting therefor in which provision is made to lock the bung ring to the container wall and also clamp it thereto to insure a liquid tight seal.

15 A further object of the invention is to provide an improved bung ring and mounting therefor which are relatively simple in construction, may be made economically and permit of ready assembly.

20 Other objects of the invention will be apparent to those skilled in the art to which my invention relates from the following description taken in connection with the accompanying drawings, wherein

25 Fig. 1 is a fragmentary plan view of a container having in one of its heads a bung ring and a mounting therefor embodying my invention.

Fig. 2 is a section on the line 2—2 of Fig. 1.

30 Fig. 3 is a fragmentary plan view of the container wall having an opening, the peripheral edge of the opening and the metal of the wall around the opening being shaped and constructed to receive my improved bung ring.

Fig. 4 is a section on the line 4—4 of Fig. 3.

35 Fig. 5 is a side elevation of my improved bung ring.

Fig. 6 is a bottom plan view of the bung ring.

Figs. 7 and 8 are elevational and plan views, respectively, of the combined locking and clamping ring.

40 Fig. 9 is a fragmentary plan view showing a different embodiment of the invention.

Fig. 10 is a section on the line 10—10 of Fig. 9.

45 Fig. 11 is a section on the line 11—11 of Fig. 9, looking in the direction of the arrows, but with the bung ring and its clamping member omitted.

Figs. 12 and 13 are side elevational and bottom plan views of the bung ring of the embodiment shown in Figs. 9 and 10.

50 Fig. 14 is a plan view of the clamping member for the bung ring shown in Figs. 9 and 10.

Fig. 15 is a section on the line 15—15 of Fig. 14.

Fig. 16 is a section similar to Fig. 10, but showing a slight modification also embodying my invention.

Fig. 17 is a side elevation of a bung ring shown in Fig. 16.

Fig. 18 is a section through the clamping member shown in Fig. 16.

Fig. 19 is a fragmentary plan view showing another embodiment of my invention. 5

Fig. 20 is a section on the line 20—20 of Fig. 19.

Fig. 21 is a fragmentary plan view of the container wall, which is similar to Fig. 3, but having cut-aways of a size to receive the bung ring shown 10 in Figs. 23 and 24.

Fig. 22 is a section on the line 22—22 of Fig. 21.

Figs. 23 and 24 are side bottom plan views, respectively, of the bung ring shown in Figs. 19 and 20. 15

In the drawings, 1 indicates as an entirety a container, such as a steel drum or barrel having a cylindrical body 1a and heads therefor at its opposite ends, only one head 1b being shown, since in the preferred construction the bung 20 ring is mounted in one head. Preferably the body and each head is united by a double seam 2.

3 indicates as an entirety a bung ring, a portion of which extends through an opening 4 formed in the head 1b, the bung ring 3 comprising a body or neck portion 3a which extends through the opening 4 and a flange 3b which rests on the marginal portion of the head or wall 1b surrounding the opening 4. The bung ring 3 is internally threaded, as shown at 3c for a 30 threaded plug or other device (not shown). Means are provided for interlocking the bung ring body 3a and walls of the container or the metal forming the periphery of the opening 4 or marginal portions of the walls surrounding 35 the opening; I also provide separate means which co-operate with the flange 3b and engage the body 3a to clamp the flange 3b to the head 1b.

Referring to Figs. 1 to 8, inclusive, which illustrate one embodiment of the invention, the metal of the wall or head 1b is distended (preferably downwardly) as shown at 5 and extended horizontally as shown at 6 to form a pocket or seat for the flange 3b. The means for interlocking the body 3a and walls of the container 45 to prevent turning of the bung ring comprise a plurality of longitudinally extending ribs 7 disposed in spaced relation and provided on the outer side of the body 3a and complementary recesses 8 formed in the horizontal wall 6 and 50 constituting cut-aways in the periphery of the opening 4. As most clearly shown in Figs. 5 and 6, each rib 7 is shaped to provide outer and side walls disposed preferably at right angles to each other. The clamping means comprises 55

a ring 9 and a securing means therefor. The inner wall 9a of the ring is complementary to the outer wall of the body 3a, so as to fit over the lower end of the latter against the lower face of the wall 6, the recesses or cut-aways 9b of the opening 9a serving to interlock the ring 9 and bung ring 3 in fixed relation. The securing means for the ring 9 is provided by riveting the lower ends of the ribs 7 over and upon the ring 9, as shown at 10. In carrying out the riveting operation, the bung ring 3 is rigidly held so that the ring 9 will be forcibly clamped toward the flange 3b, to secure the flange to the wall 6, thereby forming an effective seal. When desired a suitable gasket 11 may be provided between the flange 3b and wall 6.

Referring to Figs. 9, 10, 11, 12, 13, 14 and 15, showing another embodiment of my invention, the interlocking elements between the bung ring indicated as an entirety at 3' are reversed and the external wall of the bung ring body 3a' is threaded, as shown at 12, for a purpose later to appear. In this construction, I (a) form in the external wall of the body 3a' a plurality of recesses or cut-aways 13 extending from the free end of the body longitudinally toward and approximately to the flange 3b' and (b) provide on the periphery of the opening 4' depending arms 14, one for each recess and fitting therein as shown in Figs. 9 and 10. The arms 14 are formed integral with the horizontal wall 6', on which the flange 3b' rests, and have a width substantially equal to the width of the recesses 13, so that when the bung ring is positioned in the opening 4' with its flange 3b' in its seat, the arms 14 and side walls of the recesses 13 will be interlocked to prevent rotative movement of the bung ring. The clamping means consist of a ring 15 internally threaded and adapted to engage the threads 12 and when screwed thereon and tightened against the wall 6', as shown in Fig. 10, the flange 3b' will be secured in effectively sealed relation to the wall 6'; that is, the wall 6' will be clamped between the flange 3b' and ring 15. The outer wall of the ring 15 is formed with notches 16, whereby a suitable tool may engage the ring to turn it.

Referring to Figs. 16, 17 and 18, inclusive, I show an embodiment of my invention substantially similar to that shown in Figs. 9 to 15, except that (a) the body 3a^x of the bung ring 3^x is provided on its exterior with tapered threads 12a and the ring 15a is provided interiorly with a tapered threaded wall adapted to engage the threads 12a (as shown in Fig. 16); (b) the inner or bottom walls of the recesses 13a are parallel to the tapered threaded wall 12a; and (c) the depending interlocking arms 14a are inclined at the same angle so as to lie flat against the bottom walls of the recesses 13a. In this form of construction, the depth of the recesses 13a and thickness of the arms 14a may be relatively proportioned so that when the ring 15a is screwed into clamping relation (Fig. 16), its inner wall will engage the arms 14a and clamp them against the bottom of the recesses.

While I have shown a gasket between the bung ring flange and the adjacent wall, the gasket may be positioned between this wall and the clamping ring; or if desired gaskets may be interposed between this wall and the flange and ring.

Referring to Figs. 19 to 24, inclusive, I show an embodiment of my invention substantially simi-

lar to that shown in Figs. 1 and 2, except that I omit the clamping ring 9. In this form of construction the body 17 of the ring 3'' fits into the opening 4' of the container wall 1b' and the ribs 1' on the exterior wall of the body fit into the cut-aways 8', whereby the bung ring is interlocked with the horizontal wall 6^x, and the lower ends of the ribs are riveted over or upon such wall as shown at 10', thereby clamping the flange 3b^x of the bung ring thereto. The interposed gasket 11^x, which has a width substantially equal to the width of the wall 6^x and engages therewith throughout its circumference outside or beyond the cut-aways 8', serves to insure a liquid tight seal between the flange 3b^x and wall 6^x.

It will be noted that in my forms of construction I provide interlocking means and clamping means which conjointly secure the bung ring in rigid position. It will also be noted that the interlocking elements carried by the wall 1b are formed in or carried by the bottom, horizontal wall forming a seat for the bung ring flange; but that this wall is reinforced throughout its circumferential marginal portion by the clamping ring which clamps such portion between itself and the bung flange.

It will be obvious that the number of co-acting interlocking elements may be increased or decreased in each disclosed embodiment, depending to some degree on the size or diameter of the bung ring.

To those skilled in the art to which my invention relates many changes in construction and widely differing embodiments and applications of the invention will suggest themselves without departing from the spirit and scope thereof. My disclosures and the description herein are purely illustrative and are not intended to be in any sense limiting. No claim is made herein to the embodiments of the invention shown in Figs. 9 to 18, inclusive, as the same forms the subject-matter of a divisional application Serial No. 5,651 filed by me on the 8th day of February, 1935.

What I claim is:

1. A container having a metal wall formed with an opening, a bung ring comprising a body having a flange at one end thereof, adapted to engage one face of said metal wall, said body extending through said opening beyond the opposite face of said wall, interlocking means between said body and said wall and comprising a plurality of spaced ribs on the outer wall of said body extending longitudinally thereof and complementary recesses formed in the side walls of said opening, and a ring formed internally with longitudinally extending recesses substantially complementary to said ribs and mounted on the opposite end portion of said body in engagement with the opposite face of said wall, the free ends of said ribs being riveted over the outer face of said ring to secure it and the bung ring flange into clamped relation to said wall.

2. A container having a metal wall formed with an opening, the metal surrounding the opening being distended to provide a seat having side and horizontal walls, a bung ring having a body and a flange at one end, the body extending through said opening and the flange fitting into said seat into face to face relation with the horizontal walls thereof, interlocking elements comprising external ribs provided on and extending longitudinally of said body and complementary recesses formed in the side walls of said opening, and a ring formed internally with longitudinally

extending recesses substantially complementary to said ribs and mounted on the other end of said body in engagement with the adjacent face of the horizontal wall of said seat, the metal of the ribs being riveted over the outer face of said ring to clamp it in position.

5 3. A container having a metal wall formed with an opening, a mounting in said opening for a removable fitting; said mounting comprising an internally threaded ring having a body and a flange at one end of said body, said body extending through said opening with said flange engaging one face of said metal wall, a member on said body engaging the other face of said metal wall and interlocking means between said body and the walls of said opening and said member, respectively, whereby said ring, member and metal wall are held against relative 10 rotational movement, portions of said body being riveted over or upon said member to effect a clamping thereof and said flange against said metal wall.

15 4. A container having a metal wall formed

with an opening, a mounting in said opening for a removable device, said mounting comprising an internally threaded ring having a body extending through said opening and provided at one end with a flange disposed in engagement with one face of the wall, interlocking means between the side wall of said body and the walls of said opening, and means engaging the opposite face of the metal wall to clamp the flange against said wall, said clamping means including riveted over portions at the opposite end of said body.

10 5. A container having a metal wall formed with an opening, a mounting in said opening for a removable device, said mounting comprising an internally threaded ring having a body extending through said opening and provided at one end with a flange disposed in engagement with one face of the wall, and interlocking means between the side wall of said body and the walls of said opening, the elements of said interlocking 15 means carried by said body being extended laterally to clamp said flange against said metal wall.

20 HENRY M. DILLHOEFER.
